H. M. LOOMER,
GRINDING DEVICE FOR ROTARY CUTTERS,
APPLICATION FILED APR. 17, 1917.

1,353,254.

Patented Sept. 21, 1920.

Henry M. Loomer
By his Attorney,
Nelson McDonald

UNITED STATES PATENT OFFICE.

HENRY M. LOOMER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

GRINDING DEVICE FOR ROTARY CUTTERS.

1,353,254.

Specification of Letters Patent. Patented Sept. 21, 1920.

Application filed April 17, 1917. Serial No. 162,758.

To whom it may concern:

Be it known that I, HENRY M. LOOMER, a citizen of the United States, residing at Beverly, in the county of Essex and State 5 of Massachusetts, have invented certain Improvements in Grinding Devices for Rotary Cutters, of which the following description, in connection with the accompanying drawings, is a specification, like reference characters on the drawings indicating like parts in the several figures.

This invention relates to a device for grinding rotary cutters such, for example, as are used for trimming the edges of soles 15 in the manufacture of boots and shoes.

It is an object of the invention to provide a grinding device comprising a support movable with relation to a grinding member whereby the cutter may be accurately 20 located with respect to the grinding member and the position of the cutter readily controlled to insure proper grinding of the teeth.

More particularly, an important object of 25 the invention is to provide a device, especially adapted for use in grinding cutters of the type shown in the patent to Loomer No. 1,105,672 wherein the front face of each tooth is located at a predetermined angle 30 with respect to the axis of the cutter, which shall, nevertheless, be equally capable of use for grinding cutters of the type wherein the front face of each tooth is in a plane parallel to the axis of the cutter, as shown, for example, in the patent to Orcutt No. 295,936. The axial length of the cutters varies, however, with the character of the work and with this variation in the axial length there is, in cutters of the former type, a variation 40 in the angle between the plane of the cutting face and the plane of the end face of the cutter.

An important feature of the invention, therefore, consists in cutter supporting 45 means arranged to be readily adjusted to vary the angular relation between the axis of the cutter and the plane of its cutting edge for cutters of different sizes and shapes.

Further features of the invention relate 50 to the arrangement of the cutter supporting device whereby it may be oscillated to bring the cutter up to and beyond the grinding wheel, to resilient means whereby these oscillatory movements are effected in a pre-

determined plane, and to the organization 55 of the parts of the device rendering it simple in structure and cheap to manufacture.

The invention will be more readily understood from a consideration of the following specification taken in connection with the accompanying drawings, in which,—

Figure 1 is a perspective view of a grinding member and my novel cutter supporting device;

Fig. 2 is a vertical transverse section through the oscillatable arm of the cutter supporting device; and

Fig. 3 is a plan view showing the cutter 70 in operative relation with the grinding member.

A grinding member 10, of any form to suit the cutter to be ground, is mounted upon a shaft 12 journaled for rotation in a support 14. Power may be supplied to this shaft in any convenient manner, as, for example, by means of a belt pulley 16. The support 14 is provided with a lateral bracket 18 to which the slotted end of the two-part bracket 20 of my device may be adjustably connected by means of a bolt 22. This bracket is broken at 21 along a line parallel to the side of the slotted end and lugs 21 are provided upon the lower side of the meeting edges. One of these lugs has a rib 23 co-operating with a corresponding groove in the other lug. The latter is slotted for the reception of a bolt 25 holding the parts together. The outer end of this bracket 20 90 is preferably designed to extend in a direction substantially parallel to the axis of the grinding wheel and is grooved, as indicated at 24, to receive an auxiliary support 26 comprising a base and upstanding lugs. 95

This auxiliary support 26 is adjustably held in position in the groove by means of a bolt 28 which passes through a slot 30 extending longitudinally of said grooved portion. It will be noted that this groove 100 extends substantially at right angles to the slot in the end of the bracket 20 and that, in consequence, the auxiliary support 26 is mounted for universal adjustment in a horizontal plane. An arm 32 mounted upon a pivot pin 33 in the auxiliary support 26 is urged upwardly by means of a spring 34 until its motion is limited by engagement

of an ear upon the arm with a stop 36 in the auxiliary support. Because of the simplicity of my arrangement, the parts of my device may be made almost entirely of castings without the necessity of machine work, thus making it very inexpensive. With such a mode of manufacture, there is a possibility of lateral play between the arm 32 and its support. To insure that this may 5 have no effect upon the work and the arm moved always in a predetermined plane, the end of the spring 34 which bears against the arm 32 is arranged to be normal to the pivot 33 in the plane of a pin 35 in said arm. 10 By deflecting this end of the spring to one side of the pin 35, the spring will serve a double purpose and not only urge the arm 32 around its pivot 33 but will also urge one 15 pair of co-acting surfaces of the arm and the support into engagement to thereby assist 20 in guiding the arm for oscillation in a predetermined plane. In order to suit the convenience of a particular operative, the end of the spring may be deflected to one 25 side or the other of the pin 35 to thereby urge the arm to one side or the other and bring the corresponding co-acting surfaces of the arm and the auxiliary support into 30 engagement.

A cutter supporting table 40 is adjustably connected to the arm 32 and the parts are so arranged that the cutter supporting arm may be oscillated through a plane connecting the axis of oscillation and the axis of 35 rotation of the grinding wheel. By means of this arrangement the cutter may be oscillated through an arc intersecting the periphery of the grinding member with the result that the cutter may be brought into 40 and removed from engagement with the grinding member by one continuous movement of the cutter supporting arm.

In order to allow adjustment between the plane of the supporting table and the plane 45 of oscillation of the arm 32, the latter is grooved for the reception of a portion 42 of the table having a curved surface. In the illustrated arrangement, the portion 42 constitutes a cylindrical extension of the supporting table although it is obviously unnecessary that this exact arrangement be followed. V-shaped supporting surfaces 38 are formed within the groove of the arm 32 and the portion 42 is held in engagement 50 with said surfaces by means of an eyebolt 44 which engages the upper surface of said portion at a point intermediate the V-shaped surfaces 38. It will, therefore, be evident that a three point support is formed which 55 permits of ready and accurate adjustment of the supporting table 40 both longitudinally of the arm 42 and about its axis.

Rotary cutters, such as are to be ground, may be provided with a tapered bore. In 60 this case the diameter of this bore at one end

of the cutter is uniform in cutters of various sizes. With this in mind, I have provided a pin 46 upon the supporting table 40 designed to fit the small end of a tapered bore as well as a bore of uniform diameter, thus 70 enabling the ready location of a cutter upon the table where it may be firmly held by the workman without danger of movement during the grinding operation. The firmness with which the cutter may be positioned is 75 assisted by the fact that the pin 46 is located back from the forward edge of the table 40 and a notch 48 provided to allow the grinder to enter between the teeth of the cutter. The latter feature is claimed in the 80 co-pending application of A. Latham, Serial No. 44,936, filed Aug. 11, 1915 and assigned to the same assignee.

The particular type of grinding wheel which has been illustrated as suitable for use 85 in grinding the particular type of cutter shown in the Loomer patent is frusto-conical in shape and the larger base is the active surface used in grinding. The plane of this surface is obviously perpendicular to the 90 axis of the grinding member. In applying the bracket 20 to the support 14, the bolt 22 is so adjusted that the outer end of the bracket provided with the groove 24 is substantially parallel to the axis of the grinding 95 wheel. A cutter having been positioned upon the pin 46, the table 40 is then adjusted with respect to the arm 32 so that the angle of the cutting face of the tooth to be ground is parallel to the plane of the active 100 face of the grinding wheel and at the same time the table 40 is moved toward or away from the auxiliary support so that (see Fig. 3) the arm 32 may be oscillated from an upper position such as shown in Fig. 2 to a 10 lower position below a plane common to the axis of oscillation and the axis of the grinding wheel. In other words, the arm 32 and its table are of such length, and its axis of 11 oscillation is so located relatively to, and spaced from, the grinding wheel that the range of movement of the arm can carry the cutter down and back in a path which cuts through a plane including both the axis of oscillation and the axis of the wheel. The 11 auxiliary support 26 may now be adjusted to bring the notch of the table 40 and consequently the tooth to be ground into the plane of the active surface of the grinding wheel. The operator will then firmly grasp 12 the cutter and the table and move the same downward to grind the first tooth. This will be effected in a continuous downward movement which may be repeated if necessary. This movement causes the cutter to 12.5 sweep past the grinding wheel at such point thereof that the operator can manipulate and watch the work while standing or sitting away from the path of the dust particles resulting from the grinding operation. 130

Each tooth of the cutter will be brought into position and subjected to the action of the grinding wheel without the necessity for further adjustment aside from the movement of the cutter upon the support of the table 40. The wearing away of the grinding wheel may be compensated not only by adjustment of this table with respect to the arm 32 but also by loosening the bolt 25 and moving up the outer end of the bracket 20 with the attached parts. If the bracket was properly adjusted originally, this compensating adjustment will not disturb the relation of the cutter supporting table 40 and the grinding wheel, the movement thereof being in the plane of the active face of the wheel.

While I have herein shown and described the preferred embodiment of my invention, it will be understood that I do not desire to be limited to the exact arrangement shown but seek to cover in the appended claims all those modifications and variations which come within the true scope and spirit of my invention.

Having thus described my invention, what I claim as new and desire to secure by Letters Patent of the United States is:—

1. In a machine for grinding rotary cutters, a grinding wheel, a support, an arm pivotally mounted upon said support for movement about an axis substantially parallel to the axis of the grinding wheel, a table carried by said arm and having means for rotatively supporting a cutter, and means for adjusting said table on said arm to vary the angle between the plane of said table and the plane of oscillation.

2. In a machine for grinding rotary cutters, a grinding wheel, a support, an arm pivotally mounted upon said support for movement about an axis substantially parallel to the axis of the grinding wheel, a cutter supporting table provided with a portion having a curved surface, a groove in said arm adapted to cooperate with the curved surface on said table, and means for clamping said portion in said groove arranged to allow the angle between the plane of the table and the plane of oscillation to be varied.

3. In a machine for grinding rotary cutters, a grinding wheel, a support, an arm pivotally mounted upon said support for movement about an axis substantially parallel to the axis of the grinding wheel and provided with a cutter supporting table angularly adjustable with respect to said arm, said cutter supporting arm being arranged to permit a range of oscillation traversing a plane intersecting the axis of oscillation and the axis of the grinding wheel.

4. In a machine for grinding rotary cut-

ters, a grinding wheel, a support, an auxiliary support mounted thereon for universal adjustment in a horizontal plane, an arm pivotally mounted upon said auxiliary support, spaced V-shaped supporting surfaces on said arm, a cutter supporting table provided with a portion having a curved surface and adapted to be adjustably mounted on said supporting surfaces, and means for clamping said curved portion to said arm intermediate said supporting surfaces whereby a three point support is formed which permits of adjustment of the angle between the plane of the cutter supporting table and the plane of oscillation of the arm.

5. In a machine for grinding rotary cutters, a grinding wheel, a support, a bracket adjustably attached to said support, an auxiliary support adjustably attached to said bracket, an arm pivotally attached to said auxiliary support, resilient means for rotating said arm in one direction, a stop opposing the action of said resilient means, a notched cutter supporting table provided with a centering pin perpendicular thereto, and means for attaching said table to said arm arranged to allow adjustment of the angle between the plane of the table and the plane of oscillation.

6. In a machine for grinding rotary cutters, a grinding wheel, a support, an arm pivotally mounted upon said support for movement toward and away from said grinding wheel, said arm and support having co-acting surfaces for guiding the movements of the arm, and resilient means urging said arm in one direction around its pivot and arranged to urge said co-acting surfaces into engagement.

7. In a machine for grinding rotary cutters, a grinding wheel, a support, an arm pivotally mounted upon said support for movement toward and away from said grinding wheel, said arm and support having pairs of surfaces arranged to co-act when brought into engagement to guide the movements of the arm, and resilient means urging said arm in one direction around its pivot and arranged to urge a desired pair of co-acting surfaces into engagement.

8. In a machine for grinding rotary cutters, a grinding wheel, a support, a two-part bracket mounted upon said support, an arm pivotally mounted upon said bracket, a cutter support adjustably mounted upon said arm for movement lengthwise or angularly thereof, and means for adjustably clamping the parts of said bracket arranged to allow adjustment in a predetermined plane.

In testimony whereof I have signed my name to this specification.

HENRY M. LOOMER.
